FLUSHING APPARATUS.

No. 866,368.

Specification of Letters Patent.

Patented Sept. 17, 1907.

Application filed February 23, 1906. Serial No. 302,524.

To all whom it may concern:

Be it known that we, PETER W. LANDELL and JOHN B. WILLIAMS, citizens of the United States, residing in the city and county of San Francisco and State of California, have invented new and useful Improvements in Flushing Apparatus, of which the following is a specification.

Our invention relates to flushing apparatus for use in connection with toilets and the like. Its object is to provide a combined flush valve, tank and bowl as a unitary structure, or a combined flush-valve and tank applicable for use with bowls already installed; and which apparatus shall be simple, compact, easy of operation and capable of economically and efficiently performing its required functions.

The invention consists of the parts and the construction and the combination of parts as hereinafter more fully described and claimed, having reference to the accompanying drawings, in which—

20 Figure 1 is a vertical section on line X—X, Fig. 2, representing an apparatus of unitary structure embodying our invention. Fig. 2 is a section at right angles to the section of Fig. 1. Fig. 3 is an elevation in partial section of a modified form of our apparatus showing a 25 combined flush valve and tank applied to an ordinary bowl. Fig. 4 is a plan view of same with tank in partial section. Figs. 1 & 2 show the combination of a flush valve and bowl with a tank for storing water till needed.

The bowl A itself is similar to any other, and operates in a similar way, but we claim the distinction that, on adding an outer shell 2 around the bowl and passage leading from it to the sewer, a chamber 3 is formed under and around the bowl and said passage, with a capacity approximately of 1,226.8 cu. in., more or less, 35 or holding about 5 1/3 gallons of water, which is the capacity of the ordinary flush-tanks now in use. This chamber 3 is so designed that it is air tight at the top and has no communication with the outside, or with the bowl, except at the bottom, so that on allowing it 40 to fill with water through 4, the volume of air contained in the chamber will be compressed and will act as a cushion to drive the water out when needed. A pipe connects inlet 4 with the main; and this pipe may be provided with a valve not shown. The connection between the main and the chamber is always left open with the apparatus in use so that the water will continue to flow into the chamber until the pressure in the chamber equals the pressure in the main.

The flush valve, as shown in the accompanying drawings, is a device with the aid of which the water is drawn out of the chamber in quantities large enough to operate the toilet; the flush-valve being automatic and adjustable to allow any desired quantity, within certain limits, to flow.

55 5 represents a cylindrical valve casing formed inte-

gral with the bowl and tank 2. The bottom of the valve casing has an extension 6 of considerable inside diameter which opens into the lower part of the chamber 3. The lower end of the casing 5 is adapted to receive a brass bushing 7 which forms a seat for the valve 8 on 60 piston 8', which latter operates in a brass cylinder 9. The cylinder 9 is suitably supported in the casing 5 with respect to the valve seat and in such fashion as to leave an annular passageway 10 between the cylinder and casing 5 and to provide a suitable water connection 65 11 between passageway 10 and chamber 3 through conduit 6 when valve 8 is opened. A head or brass plug 12 screws into the upper end of cylinder 9 and is centrally cored to receive the stem 13 which carries the normally-spring-closed valve 14. This plug or head is 70 provided with radial passages 15 of suitable size communicating through ports 16 in cylinder 9 with passage 10. The plug has a ground flange 12' to seat snug on the beveled end of casing 5.

The outer end of stem 13 carries a push-button 17 75 which operates in a guide cap or guard 18, which latter is held in position by an internal flange engageable by a partial turn under the nut projection 19 on plug 12.

20 is a bushing screwed into casing 5, and into which bushing the cylinder 9 in turn is screwed and fixed; 80 the parts being arranged to form a tight joint.

21 is an annular passage formed between the flange 12' and bushing 20 and communicating with the inlet 4 exterior to chamber 3 through the port 22 which is cast or cored in the shell 2. Passage 21 communicates 85 with the valve chamber 23 in cylinder 9 through a port 24 in plug 12. A needle-valve 25 housed in guard 18 is adjustable to regulate the flow of water from the main through port 22, passage 21 and port 24 into chamber 23. Thus the actual main pressure is always maintained 90 in ports 22—21—24.

The passage 10 around cylinder 9 discharges through the enlarged port 26 into the annular flushing passage 27, which latter has the usual openings 28—29 into the bowl.

95 With the parts assembled and suitable connections made with the main, the operation is as follows: Normally valve 8 is closed to interrupt the flow of water from the tank to the bowl. Since the chamber 23 above the piston 8' remains always in communication with the 100 main (through ports 24—21—22) the pressure on the top-side of the piston equals the pressure in the tank and valve 8 remains closed. When it is desired to flush the bowl, it is only necessary to push in on the button 17, which action opens valve 14 and relieves the pressure in the top of the valve piston by allowing the water in chamber 23 to empty into port 10; inlet 24 being comparatively much smaller than the outlet through valve 14 so that the piston 8 is thrown instantly into an unbalanced state. The opening of valve 8 due to this 110 111

temporary inequality of fluid pressure on its two sides, permits the water in the tank to pass through passages 6—11—10—26—27—28—29 into the bowl to flush the latter. Inasmuch as the port 24 is of small area as compared with passages 6 & 15 and may be throttled by valve 25 to pass even a smaller quantity of water, the valve piston 8' jumps almost instantly to the top of the cylinder on the operation of the push-button. On the release of pressure on the push-button valve 14 automatically closes either by the piston striking the valve or by means of the spring 30, or by the joint action of both agencies. The water vents 6—11—10—26—&c. are of sufficient area that the emptying of the tank under the combined action of the water pressure and air pressure is very sudden. This condition insures the prompt working of the toilet, for the sudden rush of a small quantity of water, is more effective in flushing than a large quantity of water run in at a slower rate. As soon as valve 14 closes, the chamber 23 begins to fill through ports 22—21—24; and the time that it takes to fill regulates the length of the flushing period. By throttling valve 25, more or less, this period may be prolonged or shortened as the needs of a particular case require. Since the port 24 and its connections carry the full pressure of the main, and since the area of the top of the piston 8' exceeds the area of the bottom of valve 8, the latter is sure to close and remain closed until the push-button is again operated.

It will be noticed that the inlet 4 is reduced, being in practice not to exceed 3/8" in diameter, so that the water cannot flow into the tank as fast as it is forced out; consequently the water is gradually stored in the tank and against the air pressure after the operation of the valve 8 has ceased.

One advantage of this construction is that it makes it possible to connect the toilet directly to the source of water-supply through a half-inch pipe connection; for in nearly all cases a half-inch pipe is all that can be had for the toilet and this will not give a sufficient quantity of water in a given time to operate the toilet. With our combination there is no special tank necessary either in the toilet or in other parts of the building as is now generally used, thus saving extra piping of large diameters, as well as the special apparatus.

With our flush-valve applied in the manner described, a saving of water is obtained which can be obtained in no other way; for since the flushing is prompt from the beginning, the water being forced out suddenly in a comparatively large volume which has the most certain effect—the quantity needed will be the smallest possible.

The toilet is neat in appearance, prompt and reliable in its actions, and takes no more space than the stool alone. The materials and finish of the several parts of the apparatus are such as experience and the judgment of the manufacturer may dictate.

In cold climates it may be desirable to empty the contents of the tank to prevent accident by freezing. For this purpose a port 31, Fig. 2, connects the tank with the outlet 32 to the sewer; this port is normally closed by a valve 33. When it is desired to drain the tank, the valve 4^a is closed and valve 33 opened. Also the piston 8 and valve 8' may have a 1/16 inch hole 34 drilled through its center and extending throughout its entire length to make a passage for the water remaining

in the cylinder above the piston and permit it to flow down into the tank, the push-valve being left depressed.

An advantage of our flush-valve mechanism is that there is little likelihood of any of its passages being clogged by dirt; the point of the adjusting valve 25 is the only place in the passages where dirt could collect in the case of extremely dirty water being used. This valve 25 is placed however where it is easily accessible, so that by removing the top cover 18, which is easily done by hand, opening the adjusting valve one or two turns and operating the valve one or two times would wash away any dirt collected at this point. On turning the adjusting valve back to its former position, the cleansing operation is completed and the valve will operate as before. This condition is best appreciated by those having had experience with other valves of a similar type, having passages less than 1/32" in diameter and situated inside the valve, so that the whole apparatus has to be taken apart and fine wires run into the passages to clean them; putting them together in position again and re-adjusting them, which operations take time and often entail an expense in excess of the original cost of a complete apparatus.

In Figs. 3 & 4 is shown a modification of the apparatus applicable for use with bowls of toilets already installed. In this case the tank 2' is a separate structure adapted to be secured in suitable position with respect to the bowl A'. The valve casing 5' is integral with the tank and has a depending intake 6' opening into the bottom of the chamber 3'. The piston, the piston cylinder, push-button and all parts are exactly like those described in connection with Fig. 1.

Inlet to the tank from the main is through a pipe 4^a and small port 4'; this same source of water-supply under pressure is in communication with the chamber 23' through port 22' and its connections similar to those described in the first instance.

Having thus described our invention what we claim, and desire to secure by Letters Patent, is—

1. A flush valve comprising an outer cylinder, an inner cylinder open at the lower end and supported concentrically within the outer cylinder, said cylinders inclosing between them an annular discharge space, said space connecting around the lower open end of the inside cylinder with an inlet, a piston operating in the inside cylinder, a valve carried by the piston and arranged to close on a seat in said inlet, a plug screwing into the inside cylinder and having a laterally extending annular flange seating on the outside cylinder, said plug having a discharge port opening into the space behind said piston, a push valve normally closing said port, said plug also having a by-pass adapted to be connected with a source of fluid supply under pressure, said by-pass opening into the space behind said piston, and a regulating valve in said by-pass.

2. In a flushing apparatus, the combination with a bowl, of a storage tank inclosing an air pressure chamber, said tank having an inlet connected with a source of fluid supply under pressure, a valve casing arranged inside of the tank and having an enlarged-throat-portion opening downwardly into the tank near the bottom of the latter, said throat-portion having a valve-seat, said valve-casing having an inside cylinder in axial line with said valve-seat, said casing and cylinder inclosing between them an annular passage way communicating around the lower open end of said inside cylinder and through said valve-seat and throat with the interior of the tank, a piston in said inside cylinder, a valve carried by the piston and closable on said valve-seat, a by-pass connected with a source of fluid-supply under pressure and the space behind the piston, said space behind the piston having an outlet, a valve in said outlet, and a push-button to open said valve.

3. In a flushing apparatus, a combined bowl, storage-tank and flush valve casing, said storage tank, bowl and valve casing being formed integral, and said storage tank inclosing an air pressure chamber, said valve casing having a downwardly extending throat-portion opening into the lower part of the storage tank, a piston valve in the casing controlling the discharge from the tank, a push button and suitable fluid connections for controlling the movements of the piston, said casing having a discharge connected with the bowl, said storage tank connected with a source of fluid supply under pressure.

4. In a flushing apparatus, a combined bowl, storage-tank and flush valve casing, said storage tank, bowl and valve casing being formed integral, and said storage tank inclosing an air pressure chamber, said valve casing having a downwardly extending throat-portion opening into

the lower part of the storage tank, a piston valve in the casing controlling the discharge from the tank, a push button and suitable fluid connections for controlling the movements of the piston, said casing having a discharge connected with the bowl, said storage tank connected with a source of fluid supply under pressure, said bowl having a soil pipe discharge, and a valved by-pass connecting the storage tank and said soil pipe discharge. 20

In testimony whereof we have hereunto set our hand in 25 presence of two subscribing witnesses.
